UNITED STATES PATENT OFFICE.

ALBERT S. LAMBERT AND EDMUND HOFFMAN, OF BRIDGETON, NEW JERSEY, ASSIGNEES, BY MESNE ASSIGNMENTS, TO THE PRACTICAL CLOSURE COMPANY, OF SAME PLACE.

CLOSURE.

SPECIFICATION forming part of Letters Patent No. 568,486, dated September 29, 1896.

Application filed September 27, 1895. Serial No. 563,843. (No model.)

To all whom it may concern:

Be it known that we, ALBERT S. LAMBERT and EDMUND HOFFMAN, citizens of the United States, residing at Bridgeton, in the county of 5 Cumberland, in the State of New Jersey, have invented a certain new and useful Improvement in Closures, of which the following specification is a true and exact description, reference being had to the accompanying drawings, which form a part thereof.

Our invention relates to the construction of closures or stoppers used for closing bottles, cans, or other receptacles, and has for its object to provide a closure or stopper of cheap 15 simple construction, and which shall combine the elastic principle of the ordinary cork-stopper with a positively-locking union between the closure of the bottle or other receptacle to which it is applied.

20 The nature of our improvements will be best understood as described in connection with the drawings, in which they are illustrated, and in which—

Figure 1 is a central longitudinal section 25 through the neck of a bottle and our stopper applied thereto. Fig. 2 is a plan view of the stopper; Fig. 3, a side elevation thereof, showing in dotted lines the bottle-neck and the cork, which forms a part of the stopper. Fig. 30 4 is a side elevation of the metallic part of the stopper, taken at right angles to the view shown at Fig. 3. Fig. 5 is a plan view of the blank from which the metallic part of the stopper is formed, and Fig. 6 is a perspective 35 sectional view of a bottle-neck adapted for use with our improved stopper.

A indicates the neck of the bottle, which is formed with two channels A', situated opposite to each other and extending downward 40 to circumferentially-extending channels A², the upper part of which, A³, is preferably made with a downward slant, as indicated.

B is the cork, which may be of any convenient material, such as cork, rubber, or 45 anything else having the same capacity to be compressed and close the mouth of the bottle.

C is the metallic head or cap of the stopper or closure, the central part C' of which covers the top of the cork B and is provided with a

circular downwardly-extending flange C², 50 which embraces the upper part of the cork. The curved edge of the flange C² is preferably corrugated, as shown, in order to give a good holding-surface for the fingers. From the lower edge of the flange C² extend arms C³ C⁵, 55 the ends of which should be pointed, as shown, and bent inward, as indicated at c³, so as to penetrate the substance of the cork.

C⁴ C⁶ are also downwardly-extending arms from the flange of the cap, and C⁵ C⁶ are outwardly-bent portions of these arms, preferably formed by bending the metal into a fold, as indicated in Fig. 3, the extreme ends of the arms C⁴ being preferably pointed and bent inward, so as to engage the substance of the 65 cork, as is shown at C⁶.

In inserting the closure into the bottle-neck the projecting lugs C⁵ are brought to register with the grooves A', and the closure is then thrust down into the bottle-neck until the 70 lugs C⁵ come opposite to the circumferential grooves A², and by giving the upper side A³ of the said grooves a downward slant the turning of the stopper can be made to draw the cork still farther downward. Of course the 75 cork or stopper is removed by turning it until the lugs C⁵ can register with the grooves A' and then drawing it directly out.

The form of the engaging-grooves A' and A² may be considerably varied. We have 80 shown the special form illustrated in the drawings as a desirable one; but our present invention is not concerned with the conformation of the bottle-neck, and any form which will provide a groove wherein the lugs C⁵ can 85 engage themselves may be used in connection with our closure.

We prefer to construct the closure with the metal cap provided with four downwardly-extending arms; but in some cases the arms 90 C³ may be omitted, the arms C⁴ providing a sufficient union between the cork and cap-piece.

Having now described our invention, what we claim as new, and desire to secure by Letters Patent, is—

1. A closure having in combination a cork B and a metal cap C provided with depend-

ing arms C³ the ends c³ of which are bent in and inserted in the cork, and with depending arms C⁴ the ends of which are folded out to form lugs C⁵.

5 2. A closure having in combination a cork B and a metal cap C provided with depending arms C³ the ends c³ of which are bent in and inserted in the cork, and with depending

arms C⁴ the ends of which are folded out to form lugs C⁵ and then in to form anchors C⁶. 10

ALBERT S. LAMBERT.
EDMUND HOFFMAN.
